UNITED STATES PATENT OFFICE.

EDWARD M. HILL, OF BROOKLINE, MASSACHUSETTS, ASSIGNOR TO WHITING-ADAMS COMPANY, OF BOSTON, MASSACHUSETTS, A CORPORATION OF MASSACHUSETTS.

DESIGN FOR A MILITARY BRUSH.

Application filed August 22, 1928. Serial No. 27,921. Term of patent 14 years.

To all whom it may concern:

Be it known that I, EDWARD M. HILL, a citizen of the United States, residing at Brookline, in the county of Norfolk and State of Massachusetts, have invented a new, original, and ornamental Design for Military Brush, of which the following is a specification, reference being had to the drawing, forming a part thereof, of which—

Figure 1 is a plan of the military brush.
Figure 2 is a perspective of the brush.

I claim:

The ornamental design for a military brush, as shown.

EDWARD M. HILL.
